UNITED STATES PATENT OFFICE.

JAMES T. ROBB, OF FLATBUSH, NEW YORK, ASSIGNOR TO THE MITCHELL VANCE COMPANY, OF NEW YORK, N. Y., A CORPORATION OF NEW YORK.

ELECTRIC-LAMP SOCKET.

SPECIFICATION forming part of Letters Patent No. 688,125, dated December 3, 1901.

Application filed September 27, 1901. Serial No. 76,720. (No model.)

To all whom it may concern:

Be it known that I, JAMES T. ROBB, a subject of the King of Great Britain, residing at Flatbush, in the borough of Brooklyn, in the city of New York and State of New York, have invented a certain new and useful Improvement in Electric-Lamp Sockets, of which the following is a description.

My invention relates to improvements in sockets for incandescent electric lamps, and particularly for so-called "miniature" lamps for decorative and other useful purposes. At the present time, owing to the small size of the sockets which are used for miniature lamps, the contacts thereof are exposed. Modern municipal regulations require in many instances the concealment of all live conductors, so that the efforts which have been made to properly protect sockets for miniature lamps have been in the nature of makeshifts and have therefore been objectionable.

My object is to provide a very simple and cheap socket, particularly applicable for miniature lamps, and which shall be so inclosed as to effectively conceal all the conductors.

In the accompanying drawings, Figure 1 is a plan of the improved socket on an enlarged scale; Fig. 2, a vertical sectional view; Fig. 3, a section on the line 3 3 of Fig. 2; Fig. 4, a section on the line 4 4 of Fig. 2, and Fig. 5 a side elevation showing the full size of the socket.

In all of the above views corresponding parts are represented by the same numerals of reference.

A metallic base 1 is provided with a threaded nipple 2, by which the socket may be secured in place to the desired fixture. Carried upon the base 1 is an insulating annular body 3, made, preferably, of porcelain and secured in place by the countersunk screws 4 4. The insulating-body 3 is provided with two recesses 5 5, through which extend the screws 6 6 for holding the contacts in place. One of these contacts is provided with a plate 7, from which extends the contact-arm 8, bent upward and inward and formed with a flat disk-like head 9, with which the central terminal of the lamp engages. The other contact is formed of a plate 10, which is seated upon the horizontal leg of a contact-spring 11, the screw

6 passing through said spring and plate, as shown. The plates 7 and 10 are provided with binding-screws 12 12, with which the terminals may engage, the wires being obviously brought up through the nipple 2 and being passed through the porcelain body 3. Surrounding the contacts 8 and 11 is a ring 13, made, preferably, of fiber, and seated upon said ring is a sleeve 14, made, preferably, of porcelain, containing the threaded metallic sleeve 15, into which the lamp screws. The threaded sleeve 15 is formed with outstruck portions 16, which engage recesses in the porcelain sleeve 14, so as to thereby prevent the threaded sleeve 15 from turning relatively to the porcelain sleeve 14. The outturned flange of the threaded sleeve 15 is seated between the sleeve 14 and ring 13, so as to be clamped tightly in position. A metal shell 17 is provided with a flange 18 at its upper end, seated over a shoulder 19 on the sleeve 14, and has its lower end internally screw-threaded for engaging screw-threads on the base 1, as shown, whereby the shell will hold all the parts of the socket firmly and rigidly together.

In wiring the socket the shell 17 is unscrewed from the base 1 to allow the ring 13 and sleeve 14 to be removed, thereby disclosing the contacts 8 and 11. The terminals are now properly connected with the binding-screws 12 12, after which the ring 13 and sleeve 14 are replaced and held securely in position by the shell 17, the contact-spring 11 making contact with the threaded metal sleeve 15.

Having now described my invention, what I claim as new, and desire to secure by Letters Patent, is as follows:

1. As a new article of manufacture, an electric-lamp socket, comprising an insulating-body, a central contact carried by said body, a contact-spring carried by said body, an insulating-ring inclosing said contact and contact-spring, a threaded metal sleeve above said ring making contact with the contact-spring, and an insulating-sleeve surrounding said threaded metal sleeve and holding the latter in engagement with said ring, substantially as and for the purposes set forth. 100

2. As a new article of manufacture, an electric-lamp socket, comprising an insulating-

- body, a central contact carried by said body, a contact-spring carried by said body, an insulating-ring inclosing said contact and contact-spring, a threaded metal sleeve above 5 said ring making contact with the contact-spring, an insulating-sleeve surrounding said threaded metal sleeve and holding the latter in engagement with said ring, and a metal shell engaging said insulating-sleeve for 10 clamping the threaded metal sleeve between said insulating sleeve and ring, substantially as and for the purposes set forth.
3. As a new article of manufacture, an electric-lamp socket, comprising an insulating- 15 body, a central contact carried by said body, a contact-spring carried by said body, an insulating-ring inclosing said contact and contact-spring, a threaded metal sleeve above said ring making contact with the contact- 20 spring, an insulating-sleeve surrounding said threaded metal sleeve and holding the latter in engagement with said ring, and means for preventing relative rotation of said sleeves, substantially as and for the purposes set forth.
- 25 4. As a new article of manufacture, an electric-lamp socket, comprising an insulating-body, a central contact carried by said body, a contact-spring carried by said body, an insulating-ring inclosing said contact and contact-spring, a threaded metal sleeve above 30 said ring making contact with the contact-spring, and an insulating-sleeve surrounding said threaded metal sleeve and holding the latter in engagement with said ring, the threaded 35 metal sleeve being provided with outstruck portions engaging recesses in said insulating-sleeve for preventing relative rotation of said sleeves, substantially as and for the purposes set forth.
- 40 5. As a new article of manufacture, an improved electric-lamp socket, comprising a metal base, an insulating-body carried by said base, an insulating-ring surmounting the body, an insulating-sleeve carried by said 45 ring, means for clamping said sleeve and ring upon said insulating-body, a threaded metal sleeve carried within said insulating-sleeve, and a central contact carried by said body, substantially as set forth.
- 50 6. As a new article of manufacture, an improved electric-lamp socket, comprising a metal base, an insulating-body carried by said base, an insulating-ring surmounting the body, an insulating-sleeve carried by said 55 ring, a metal shell having a threaded connection with said base and engaging said sleeve for clamping said sleeve and ring upon said insulating-body, substantially as set forth.
- for clamping said sleeve and ring upon said insulating-body, a threaded metal sleeve carried within said insulating-sleeve, and a central contact carried by said body, substantially as set forth. 60
7. As a new article of manufacture, an improved electric-lamp socket, comprising a metal base, an annular insulating-body carried by said base, two metal plates secured to 65 said body, a contact extending from one of said plates, a contact-spring carried by the other of said plates, an insulating-ring surrounding said contact and contact-spring, an insulating-sleeve surmounting said ring, and 70 a threaded metal sleeve carried within said insulating-sleeve and clamped in position between the same and said ring, substantially as set forth.
8. As a new article of manufacture, an improved electric-lamp socket, comprising a metal base, an annular insulating-body carried by said base, two metal plates secured to 75 said body, a contact extending from one of said plates, a contact-spring carried by the other of said plates, an insulating-ring surrounding said contact and contact-spring, an insulating-sleeve surmounting said ring, a threaded metal sleeve carried within said insulating-sleeve and clamped in position 80 between the same and said ring, and means for clamping said insulating sleeve and ring upon the insulating-body, substantially as set forth.
9. As a new article of manufacture, an improved electric-lamp socket, comprising a metal base, an annular insulating-body carried by said base, two metal plates secured to 85 said body, a contact extending from one of said plates, a contact-spring carried by the other of said plates, an insulating-ring surrounding said contact and contact-spring, an insulating-sleeve surmounting said ring, a threaded metal sleeve carried within said insulating-sleeve and clamped in position 90 between the same and said ring, and a metal shell having a threaded connection with said base and engaging said sleeve for clamping said sleeve and ring upon the insulating-body, substantially as set forth. 95
- This specification signed and witnessed this 25th day of September, 1901.
